DEFROSTER FOR REFRIGERATORS OR THE LIKE

R Stuart Davis, Jr., 32021 Weston Drive,
Birmingham, Mich.

Filed Mar. 27, 1964, Ser. No. 79,225

Term of patent 7 years

(Cl. D67—2)

FIG. 9

FIG. 1

FIG. 4

FIG. 2

FIG. 3

FIG. 6

FIG. 5

FIGURE 1 is a perspective view of a defroster for refrigerators or the like, embodying my inventive design;

FIGURE 2 is a side elevational view thereof, the center section being omitted for convenience of illustration;

FIGURE 3 is an elevational view taken from one end thereof;

FIGURE 4 is an elevational view taken from the other end thereof;

FIGURE 5 is a bottom plan view of FIGURE 2;

FIGURE 6 is a side elevational view of a modified form of the defroster for refrigerators or the like shown in FIGURES 1-5, the center section being omitted for convenience of illustration;

FIGURE 7 is an elevational view taken from one end of FIGURE 6;

FIGURE 8 is an elevational view taken from the end opposite that shown in FIGURE 7; and

FIGURE 9 is a top view of FIGURE 6.

The conventional electric cord is shown as broken away in FIGURES 1, 2, 3, 5, 6, 7, and 9 for convenience of illustration.

I claim:

The ornamental design for a defroster for refrigerators or the like, as shown and described.
